(57) **CLAIM**

The ornamental design for a resin building, as shown and described.

DESCRIPTION

FIG. 1 is a back perspective view of a resin building showing my new design;

FIG. 2 is a front view thereof;

FIG. 3 is a right side view thereof, the left side view being a mirror image;

FIG. 4 is a back view thereof; and,

FIG. 5 is a top view thereof.

The phantom line representations in FIGS. 1-5 are exemplary and form no part of the invention.

1 Claim, 5 Drawing Sheets
